UNITED STATES PATENT OFFICE.

EDWARD E. BRADLEY, OF STONINGTON, CONNECTICUT, ASSIGNOR TO
GEORGE DRAPER & SONS, OF HOPEDALE, MASSACHUSETTS.

SPINDLE.

SPECIFICATION forming part of Letters Patent No. 333,914, dated January 5, 1886.

Application filed April 21, 1884. Serial No. 128,745. (No model.)

To all whom it may concern:

Be it known that I, EDWARD E. BRADLEY, of Stonington, county of New London, State of Connecticut, have invented an Improvement 5 in Spindles, of which the following description, in connection with the accompanying drawings, is a specification, like letters on the drawings representing like parts.

This invention relates to that class of spindles which is composed of two parts, one part 10 having an attached sleeve-whirl, while the other part carries the bobbin.

My invention consists, essentially, in a spindle provided with a sleeve-whirl and a supporting-case therefor, combined with a bobbin-carrying spindle having an attached foot secured to the sleeve-whirl loosely, and with an interposed india-rubber or flexible packing, as will be described.

20 Figure 1 represents in elevation the two parts of my improved spindle, the supporting-case, the rail, and parts attached to the spindles being in section; and Fig. 2 is a like view of a modification.

25 The spindle A, placed in the bushing a' in the supporting-case B, secured to the rail C, has attached to it a sleeve-whirl, D. The upper end of the sleeve-whirl is provided with an india-rubber or yielding packing, b, and has 30 secured to it by screws d the foot c of the bobbin-carrying spindle E, the spindle A thus driving spindle E, the diameter of the screw-holes in the foot being greater than the diameter of the screw d, so that the bobbin-carrying 35 spindle may tip or turn sufficiently, as is well understood, to permit it to center itself to its load. This foot c has a sleeve, c², which is extended downwardly about and to more or less inclose the sleeve of the whirl, and, preferably, 40 as represented in Fig. 1, the lower end of the sleeve c² will be provided with an elongated collar, as at c³, between which and the sleeve of the whirl is interposed a piece of india-rubber or other yielding packing, h, which 45 affords the spindle E an opportunity to center itself. In some instances, the packing h being employed, the washer b may be omitted.

The interior of the sleeve c² and the exterior of the upper end of the sleeve of the whirl are 50 of such relative diameter that the interior surface of the said sleeve c² and the exterior of

the sleeve of the whirl do not touch when the bobbin-carrying spindle is in true central position, the space between the said surfaces to be operative for the purpose stated requiring to be not more than one one-hundredth of an inch. 55

In the drawings the space referred to is shown exaggerated; but in practice it will be understood that the said space is too small to be easily discernible.

A spindle divided into two parts and combined as described and represented is undisturbed by the strain or pull of the band, and may be run very steadily. If desired, the 65 sleeve c² may be shortened, as in Fig. 2, and the packing h be omitted.

In another application, No. 128,744, filed concurrently herewith, I have shown the sleeve attached to the bobbin-carrying spindle as extended downwardly about the sleeve of the whirl, and also a flexible washer or packing interposed between the top of the sleeve of the whirl and the foot of the bobbin-carrying spindle of the whirl, but have not therein claimed 75 such features, reserving them for this patent.

I am aware that a whirl-spindle has had a projection to enter a notch at the lower end of a bobbin-carrying spindle, as in United States Patents Nos. 255,074 and 288,230. 80

The supporting-case may be supplied with oil in any usual manner.

I claim—

1. The supporting-case, spindle A, and its attached sleeve-whirl, combined with the bobbin-carrying spindle having a foot and attached sleeve, the latter being extended downwardly about the sleeve of the whirl, and with means to connect the parts to effect the rotation of the bobbin-carrying spindle from the 85 spindle A, substantially as described.

2. The supporting-case, spindle A, and its attached sleeve-whirl, and the bobbin-carrying spindle E, and its foot and downwardly-extended sleeve, combined with the packing 95 h, interposed between the sleeve of the spindle E and the sleeve of the whirl, substantially as described.

3. The supporting-case, the spindle A, its attached sleeve-whirl, and the bobbin-carrying spindle provided with a foot and a sleeve, combined with an elastic washer interposed 100

between the lower end of the said foot and the top of the sleeve of the whirl, and with means to effect the rotation of the bobbin-carrying spindle from the spindle A, substantially as 5 described.

4. The supporting-case, the spindle A, and its attached sleeve-whirl, and the bobbin-carrying spindle E and its attached foot, combined with the elastic washer interposed between the foot of the spindle E and the upper

end of the sleeve of the whirl, and with screws *d* in holes of greater diameter in the said foot, substantially as described.

In testimony whereof I have signed my name to this specification in the presence of two subscribing witnesses. 15

EDWARD E. BRADLEY.
